UNITED STATES PATENT OFFICE.

HARRY J. SHELTON, OF UNIVERSITY CITY, MISSOURI.

CRUSHER.

Application filed September 28, 1927. Serial No. 222,431.

This invention relates to certain new and useful improvements in crushers for rock, coal and other material, the peculiarities of which will be hereinafter described and 5 claimed.

The main object of my invention is to provide an improved travelling breaker plate of pivotally connected impact plates co-acting with the crushing elements and having pro- 10 teeted joints at the side edges; secondly, to a compound impact plate providing a face plate subject to wear, adapted to be readily removed and another set in place; thirdly, to means for supporting said impact plates at 15 or near their ends; fourthly, to operative driving connections for said impact plates; fifthly, to means for adjustably supporting the impact plates and driving means; and to other points hereinafter described and 20 claimed.

In the accompanying drawings on which like reference numerals indicate corresponding parts, Fig. 1 represents a front view of a crusher with my improvements applied 25 thereto, with parts broken away to show the construction; Fig. 2 a vertical view inside the housing at 2—2, Fig. 1; Fig. 3 a side elevation of the right-hand side of Fig. 1; Fig. 4 a partial plan view of the right hand of the 30 driving head; Fig. 5 a bottom plan view of the face plate portion of my impact plate; Fig. 6 an edge view of the same; Fig. 7 a plan view of the base plate portion of my impact plate with location of the face plate in- 35 dicated by dash lines; Fig. 8 an edge view of the same; Fig. 9 a bottom plan view of the same; Fig. 10 a cross section at the center on the line 10—10; Fig. 11, a cross section on the line 11—11; and Fig. 12 an end view of 40 the same.

Referring to the drawings, the numeral 1 designates a crusher shaft mounted in suitable bearings and carrying discs 3 having rods 4 on which are pivoted hammers 5 forming 45 the preferred form of rotating crushing elements. These constitute the rotor which is rotated in the direction of the arrows, by belted pulley or direct connection to a motor in the usual manner, at 1200 R. P. M., more 50 or less, according to the diameter of the hammer circle and the kind of material to be reduced. A casing is formed by the sides 6, top 7 and back 8, while an arcuate cage of bars 9 with suitable openings, is mounted in 55 grooves in the sides in the usual manner. The front bar of this cage is triangular or

pointed to serve as a scraper as described later.

Between the sides at the front is mounted a series of impact plates pivotally connected to form an endless chain of plate steeply inclined and travelling slowly downward in the direction of the arrow, in close proximity to the hammer circle, and constituting a travelling breaker plate, between which and the hammers or other rotary beaters, the material is primarily crushed and proceeds to the cage below for further reduction or to escape through the openings between the bars. Since the wear is mainly on the face, 70 each of these impact plates preferably consists of two parts: an upper face plate 12, preferably of manganese steel to serve as a wear plate; and a lower base plate 13, preferably of cast steel, on which the face plate is detachably mounted in any suitable manner, preferably by several tenons 14 depending in a line from the under side of the face plate and extending through mortise holes 15 in the base plate beyond 75 the lower face, so as to allow a rod 16 to be passed through aligned holes in the tenons and bear against the under side of the base plate as shown in Fig. 1. Cotter pins keep the rod from shifting. The 80 mortise holes are located to one side of a web and beam truss 17, centrally depending from the base plate lengthwise, having its greatest depth midway of the ends which have cross webs 18 and 19 forming recesses in which 85 are preferably mounted respective rollers 20 on center shafts 21 secured by cotters as indicated. The holes 22 in these webs line up with the holes in the tenons when in place and are exposed at the front of the crusher 90 when they pass a recess or other opening in the side housings so as to allow insertion and removal of said fastening rod 16. Inter- 95 matching rounded tongues 23 and 24 on the side edges of the base plate, preferably at the 100 ends, allow hinged connection between adjacent base plates on center pins through holes 25 and 26 that center substantially with the side edges of the base plate 13 which are also beveled off at 27 on the lower side accordingly.

At each end of the base plate at one side of the center is an extension 28, preferably triangular, from the web 18, having a vertical rectangular tooth 29 extending above 11 the upper face of the base plate substantially the thickness of the face plate 12, which has

a rectangular matching hole or notch 30, Fig. 5, accordingly. In each impact plate the face portion is offset from the lengthwise center and thus overlaps at one side edge the adjacent base plate portion, and its other side edge sets back from the same side edge of the base plate, as shown in Fig. 1, and indicated by dash lines in Fig. 7. On each side edge of the impact plate two abutting edges 10 with a connecting face are thus formed making a zig-zag joint for the impact plates. The lower face of the wear plate and the upper face of the base plate lie close together —practically in the same plane,—so that the 15 wear plate beds down solidly on the base plate to withstand the impact of crushing the material under the blows of the hammers.

A drive chain 31 is mounted above the extension 28 from each end of the base plate and 20 is supported thereby on the tooth 29. This chain has a pitch of substantially one-half the width of the base plate, so that two links of the chain correspond to the distance between centers of the hinge holes 25 and 26, and one 25 link is engaged by the tooth 29 while the other is adapted to be engaged by a tooth of sprocket wheels. Therefore alternate links engage teeth 29 and teeth of sprocket wheels. The top of the end extensions 28 is below the top 30 surface of the base plate a depth corresponding to that of the driving chain used, which thus lies in an end recess between the two plates and is covered by the face plate in position; and alternate links are engaged by the 35 teeth or other means connecting these plates through said links. The face plate engages the top of the tooth 29 so that the pull of the chain on tooth 29 is resisted by the reaction of the face plate at the top of the tooth 29, 40 and by the extension 28 at the base of said tooth. In other words, the tooth 29 is held by the face plate in side contact with its top while the base is held by the supporting extension 28, similar to a beam fixed at both 45 ends, and thus secures double the strength of a tooth alone.

The chain is not otherwise secured to the compound impact plates and can be laid down on the teeth 29 before the face plates 50 are put on the base plates and can be simply lifted off the teeth 29 when worn, by first removing the face plates; meantime the chain is securely engaged by alternate links to the compound plates since it lies in the guarded 55 space between the ends of both the plate members with said teeth passing through alternate links and connecting both of said members. This construction allows the use of any suitable chain of standard manufacture—such as that known as "Link-belt,"—without any alteration of the commercial article, thus securing strength and ready replacement of the chain.

This driving chain 31 at each end of the 60 impact plate passes over suitable driving

sprockets 32, keyed to a driving shaft 33 mounted in bearings 34 on the side housing, and preferably driven through a flexible coupling 35 by a reduction gear motor or otherwise, at a comparatively slow speed such as 70 one revolution per minute. The sprocket wheels are notched between the sprocket teeth, to receive the triangular extensions 28 of the base plates as shown in Figs. 1, 2 and 3. Corresponding sprocket wheels 36 are rotatably mounted on a preferably stationary or non-rotary lower shaft 37, adjustably mounted so as to be adjusted vertically to tighten the driving chains, and laterally toward and away from the hammer circle to 80 regulate the fineness of the crushed product. In the latter adjustment, the filler plate 38 of the cage is varied or the spaces of the cage bars are otherwise adjusted to correspond. The front bar extends upward adjacent to the 85 travelling impact plates and is adapted to serve as a scraper for the material adhering to the face of said plates.

These driving sprockets and corresponding carrying sprockets are mounted in offsets 90 39 (Fig. 4) of the side housing so that the sides 6 with liners 40 overlap the impact plates. The top ends of the teeth 29 in the matching notches 30 of the face plates are thus protected from battering by rock being 95 crushed on these vertically inclined impact plates mounted in this widened front of the crusher, and crushed material is not readily forced between the guarded ends of the impact plates and the side housings. Any fine feed material entering the offset finds exit past the ends of the impact plates through the clearance space 41, Fig. 1. The necessary play at the sides of the impact plates is protected by the overlapping or zig-zag form of 100 the side edges as above described so that comparatively little material finds its way into the space between the sprocket wheels in practical operation.

The ends of the impact plates are supported directly on track beams 42 of I-beam or other cross section, without intermediate support for the impact plates, the beams at their upper ends having pivotal bearings on the driving shaft 33 or otherwise adjacent 11 to the sprocket wheels, and their lower ends slotted for slidably embracing or otherwise the lower shaft 37 as indicated in Fig. 2. The lower shaft is preferably square between the sprocket wheels. Upon the edge flange of 12 these hanging pivoted beams, track the said rollers 20 that support the web portions 18 and 19 adjacent to said flange and preferably just out of sliding contact therewith. This rolling contact on said track beams makes a 13 large reduction of power required for the travel of the impact plates as compared with a prior construction having a platen supporting the impact plates between the side housings, as the friction of sliding contact of such 14

plates on such a platen under the pressure of the hammer blows in crushing rock, is very considerable. The wear of such plates and platen in sliding contact is also increased by 5 the material forced through the abutting plain joints of said prior construction which increases the power required to move such plates and also accumulates inside the lower 10 loop of such series of plates causing trouble and difficulty of removal. My construction 15 of zigzag joints at the side edges of my plates practically prevents material passing inside through the joints.

For adjusting the lower shaft to and from 15 the hammers any suitable means may be used, such as a flanged head 43 on a screw 44 secured by nuts to the webs of the bearing pedestal or elsewhere. The vertical adjustment is obtained by a screw 45 operating in a 20 nut slotted in a boss 46 on the side housing, or otherwise. Since the lower ends of the track beams are slidably engaged to this lower shaft, the lateral adjustment of lower shaft and beams is simultaneous and their relation laterally is maintained during adjustment, while 25 allowing variation vertically by operating said screws 45 as stated.

I claim:

1. A crusher comprising an endless series 30 of vertically inclined travelling impact plates provided with supporting rollers near their ends and end extensions adapted for chain engagement projecting beyond said rollers, track beams for said rollers, removable driving 35 chains detachably connected to and supported by said extensions, and means to operate said chains.

2. A crusher comprising side housings having a vertically inclined offset in each side 40 forming overlapping shoulders and a widened front, an endless series of vertically inclined travelling impact plates having their ends mounted within said offsets and guarded by said shoulders, supporting rollers mounted 45 near the ends of said plates, adjustably mounted track beams for said rollers, detachable driving chains supported on said plates and within said offsets, upper and lower shafts carried by the housings, and sprockets 50 mounted on said shafts opposite said shoulders in the housings.

3. A crusher comprising an endless series 55 of vertically inclined travelling plates each consisting of a base plate and a detachable face plate,—the base plate being provided with supporting rollers near its ends and also end extensions projecting beyond said rollers and each extension having a tooth projecting upwardly and engaging the face plate,—detachable driving chains supported on said extensions and engaging said teeth between the face plates and base plates, and driving means therefor, substantially as described.

4. A crusher comprising an endless series 60 of vertically inclined travelling impact plates

each consisting of a base plate and a face plate,—the base plate having supporting means near each end and a depending web deepest in the middle between said means, and also having mortise holes,—and the face plate 70 having depending tenons matching said mortise holes and extending below the base plate, and fastening means for said tenons.

5. A crusher comprising an endless series 75 of vertically inclined travelling impact plates each consisting of a base plate and a detachable face plate set laterally off center thereon,—each base plate having a recess at each end below its top surface and covered by the corresponding end of the face plate, a driving 80 chain at each end mounted between said plates in said recess, and means passing through alternate links of said chain and connecting said plates, substantially as and for the purpose described.

6. A crusher comprising side housings each 85 having an offset forming a widened front and guarding shoulders extending from top to bottom, an endless series of compound travelling plates mounted in said widened front 90 and each consisting of a base plate and a detachable face plate set laterally off center thereon,—the ends being mounted in said offsets and connecting means at said ends being 95 guarded by said shoulders, substantially as described.

7. A crusher comprising an endless series 100 of vertically inclined travelling impact plates each consisting of a base plate and a detachable face plate—the base plate having aligned mortise holes through the middle and also cross webs near each end provided with rollers mounted therein and holes in line with the mortise holes,—and the face plate having depending aligned tenons matching 105 said mortise holes and provided with holes aligning with the holes in said cross webs, and a rod passing through the said holes in tenons and cross webs and removable at the front of the crusher, substantially as described.

8. A crusher comprising an endless series 110 of vertically inclined travelling impact plates provided with supporting rollers, an upper driving shaft and a lower shaft—both operatively connected to said impact plates,—track beams for said rollers pivoted near their upper ends and slidably engaging said lower shaft, and means to adjust the lower shaft laterally and simultaneously the track 115 beams.

9. A crusher comprising an endless series 120 of vertically inclined travelling impact plates provided with supporting rollers, an upper driving shaft and a lower shaft—both operatively connected to said impact plates,—track beams for said rollers pivoted near their upper ends on said driving shaft and having a slotted lower end slidably engaging said lower shaft, and means to adjust 125

the lower shaft laterally and simultaneously
the track beams.

10. A crusher comprising side housings, an
endless series of travelling impact plates, an
upper driving shaft, a lower non-rotary
square shaft having round ends extending
through the side housings, sprocket wheels
rotatably mounted on said round ends adjacent
to the side housings, adjustable track
10 beams pivotally mounted near their upper
ends on said driving shaft and having slotted
ends slidably engaging said lower shaft, bearings
for the ends of the lower shaft, and
means to adjust said bearings vertically and
15 laterally,—the lateral adjustment only affecting
said track beams also.

11. A crusher comprising side housings, an
endless series of travelling vertically inclined
impact plates mounted therein, and a cage
20 bar having a sharply angular side edge with
one face adjacent to the path of said travelling
impact plates and adapted to scrape off
the adhering material being crushed.

12. A crusher comprising an endless series
25 of travelling impact plates each consisting of
a base plate and a detachable face plate—the
base plate having mortise hole at one side of
the central plane and the face plate having
depending tenons extending through said
30 mortise holes and below the base plate,—the
face plate being in substantially close contact
with the base plate forming a solid compound
plate adapted for impact and also disposed
laterally off center from the base plate, and
35 fastening means therefor, substantially as de-
scribed.

13. A crusher comprising side housings
having offsets forming guarding recesses, an
endless series of travelling impact plates
40 hinged together and having their ends
mounted in said recesses and each plate con-
sisting of a base plate and a superposed de-
tachable face plate set off center in close

contact therewith—the meeting faces of said
plates being in substantially the same plane 45
and making a solid compound impact plate
in the portion subject to impact, substantially
as described.

14. A crusher comprising a series of trav-
elling impact plates each consisting of a base 50
plate and a superposed face plate detachably
mounted thereon,—the ends of the base plates
being separated from the adjacent ends of
the face plates by a space sufficient to receive
a link-belt chain, and each space provided 55
with a tooth connecting both plates and de-
tachably engaging the interposed chain, sub-
stantially as described.

15. A crusher comprising a series of com-
pound travelling impact plates each consist- 60
ing of a base plate and a face plate detach-
ably mounted thereon,—said plates being
separated at their ends by a space adapted
to receive a link-belt chain,—the base plate
having a tooth extending through said space 65
and engaging the face plate and adapted to
pass through a link of the chain and resist
the pull of the chain at the middle of the
tooth, substantially as described.

16. A crusher comprising a compound 70
travelling impact plate adapted to be sup-
ported at its ends only and consisting of two
plates in close contact with each other be-
tween the points of support,—one of said
75 plates having end extensions beyond said
points of support and spaced from the other
plate, and each extension having a tooth en-
gaging the other plate and adapted to de-
tachably engage a link of chain interposed
between said extension and the other plate, 80
and means to detachably secure said plates
together, substantially as described.

In testimony whereof I have affixed my
signature.

HARRY J. SHELTON.
